Patented Dec. 13, 1921.

UNITED STATES PATENT OFFICE.

AMOS F. DIXON, OF NEWARK, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,400,035.

Specification of Letters Patent. Patented Dec. 13, 1921.

Application filed November 20, 1917. Serial No. 202,941.

To all whom it may concern:

Be it known that I, AMOS F. DIXON, a citizen of the United States, residing at Newark, in the county of Essex and State of New Jersey, have invented certain new and useful Improvements in Telegraph Systems, of which the following is a full, clear, concise, and exact description.

This invention relates to telegraph systems and more particularly to improvements in 10 multiplex systems.

The object of this invention is the provision of a simple arrangement for driving two or more distributors in synchronism, 15 and one which will be suitable for use in systems where economy in line time is not a controlling factor.

In the system of this invention, one of the distributors acts as a master distributor and 20 sends impulses over a line to the other distributors. Such impulses are preferably sent out in groups to alternate with groups of message impulses, the momentum of the controlled distributor being relied upon to maintain the continued isochronous motion during 25 the time that message marking impulses are being transmitted.

In the specific embodiment of the invention herein described, the transmitter is 30 equipped with four groups of segments arranged alternately to transmit message impulses and control impulses. The receiving distributor is similarly equipped with four groups of segments arranged alternately to 35 receive message impulses and control impulses. It will thus be seen that in this specific arrangement, the line is available for the transmission of message impulses during half of the time and that the other half of the 40 time is employed in transmitting control impulses.

It will be obvious, however, that the system is not limited to the employment of four groups of impulses, but that a greater or less 45 number may be employed, depending upon the requirements of the service. It will also readily appear to those skilled in the art that the two sets of segments, instead of being arranged in groups, may be arranged so as 50 to alternately send out a message and a control impulse.

This invention is illustrated diagrammatically in the accompanying drawing in which only so much of a telegraph equipment is

shown as will be necessary to a clear understanding of this system.

Referring to the drawing, the reference character A indicates a telegraph station at which a main line 1 terminates in a polar duplex equipment comprising a polarized 60 relay 10 and an artificial line AL. A distributor 20 of the rotary type is included in circuit with the neutral point 13 of the duplex equipment and operates to impart outgoing impulses to the main line 1. A distributor 30 included in circuit with the armature of the line relay 10 controls the reception and distribution of telegraphic impulses incoming from the main line 1.

The line 1 extends to a second station B 70 and there terminates in a polar duplex equipment comprising a polarized line relay 40 and an artificial line AL. A distributor 70 connected to the neutral point 43 of the duplex equipment controls the imparting of outgoing impulses to the line 1, and a distributor 80 included in circuit with a local contact 44 of the line relay 40 serves for the reception and distribution of impulses incoming from the main line 1.

The present system applies more particularly to printing telegraphs and message transmission is based on the well known Baudot system in which a five-unit code comprising permutations of positive and negative impulses of current is employed. In conformity with such five-unit code, wherein each character is distinguished from all other characters by a particular permutation of the impulses and these impulses act upon the 90 selecting mechanism of a receiving equipment to recompose the impulses into a printed character, the distributors are provided with suitably segmented rings divided into quadrants, each quadrant corresponding with 95 an interval of five impulses. Accordingly, at the transmitting distributor 20 and 70 five segments in each of the quadrants C and E may be connected respectively with different transmitters, or one transmitter at each distributor may be interconnected in derived 100 circuit manner to the segments in both quadrants C and E to prepare permutations of current polarities at these segments to be successively imparted to the line 1 as the trailer 105 arms 21 and 71 sweep through their respective quadrants. The same service arrangement applies to the receiving distributor 30

and 80 except that telegraph receivers or printers would, of course, be connected to the segments in the quadrants C and E of these distributors, and the trailer arms 31 and 81 in sweeping through their respective quadrants would distribute impulses received from the line circuit 1 to associated printing mechanisms.

In describing the present system let it be assumed that the distributors 20 and 30 at A are driven by a suitable constant speed motor (not shown), as a phonic wheel under control of a tuning fork, as well understood in the art. Accordingly, such driving means will cause the trailer or contactor arms 21 and 31 respectively of these distributors to rotate in synchronism one with the other at a uniform speed and, say, in a clockwise direction. At the distributor 20 it will be noted that in the quadrants D and F the first and following alternate segments, progressing clockwise, are included with a source of negatively poled grounded current 2, and that the second and following alternate segments are included with a positively poled grounded source 3. Therefore, when the trailer arm 21 sweeps over the segments in these quadrants alternate negative and positive current impulses will be transmitted by way of the trailer arm 21, collector ring 22, point 27 and a switch blade 26, a point 15 and a switch blade 16, to the neutral point 13 at the relay 10. From this point an impulse divides, a portion of the current traversing the relay coil 12 and artificial line AL to earth, while an equal portion traverses the relay coil 11, main line conductor 1, thence through the serially connected coils 41 and 42 of the line relay 40 and the artificial line AL to earth. Owing to the duplex balance the line relay 10 is not affected by these currents, while the line relay 40 responds thereto and moves its armature to engage the contact stops 44 and 45 in phase with alternations in polarity of the impulses imparted to the line 1 by the distributor 20. Let it be further assumed that the distributors 70 and 80 at B are running in synchronism with the distributors at A, as will presently be apparent. Accordingly, the trailer arm 81 of the distributor 80 will be in the quadrant D, corresponding with such time as the trailer arm 21 of the distributor 20 is in its quadrant D. While the trailer arms are passing through the quadrants D each negative impulse from the distributor 20 acts through the relay 40 to establish a circuit which may be traced from a source of grounded current 49, the contact 45 of the relay 40, the winding of a motor control relay 50, the contacts 61 of a switch 60, a conductor 77, a segment 82 of the distributor 80, the trailer arm 81, to a grounded contactor section 83. In responding to current through this circuit the relay 50 closes its contacts

52, thereby establishing a circuit from a current source 57, the winding of a motor magnet 55 of a motor 53, the contacts 52 of the relay 50, the contacts 61 of the switch 60, thence over the conductor 77 to earth at the distributor 80 as already traced for the relay operating current. The magnet 55 thus energized impels a rotating armature 54 forward in a clockwise direction. On cessation of the negative impulse in the line 1 and the imparting of a positive impulse thereto by the distributor 20, the armature of the relay 40 separates its contact 45 and idly closes its contact 44. Opening of the contact 45 permits the relay 50 to release, thereby separating its contacts 52 to disconnect the motor magnet 55 and to establish a circuit from the current source 57 through a motor magnet 56, by way of a conductor 62, the contacts 75 of the key 60, the contacts 51 of the relay 50, the contacts 61 of the switch 60 and conductor 77 to earth at the distributor 80 as already traced. Such alternate energization of the magnets 55 and 56 causes the rotation of the armature 54 after the manner well understood by those familiar with the La Cour motor.

During periods the trailer arms may be in their respective quadrants D or F, engagement of the contact 44 of the relay 40 is non-effective, since the circuit which extends from this contact, by way of switch 46, and conductor 58, is open at collector ring sections 85 and 86 in the message receiving quadrants C and E of the distributor 80. From the foregoing description it will be clear that in phase with the movement of the trailer arm 21 of the distributor 20 in passing over the segments in quadrants D and F the driving magnets 55 and 56 of the motor 53 will be alternately energized to operate the revolving armature 54 which will be understood to be mechanically connected in a manner suitable to drive the trailer arms 71 and 81 of the distributors 70 and 80, respectively. A suitable balance or fly wheel (not shown) may be employed to steady the operation of the motor 53 and also supply the momentum necessary to properly continue rotation of the armature 54 during the one-quarter periods that the trailer arm 21 of the distributor 20 is traversing the quadrants C and E in the transmission of message impulses over the line 1 to a receiver which may be assumed as connected to the corresponding quadrants of the distributor 80.

At the distributor 70 all segments in the quadrants D and F are connected with a grounded source of negatively poled current 73, therefore, on respectively entering these quadrants the trailer arm 71 establishes a circuit from the source 73 by way of the collector ring 72, a point 74 and switch blade 76, a point 65 and switch blade 66 to the neutral point 43 of the duplex equipment.

From this neutral point the current divides equally, one portion traversing the relay coil 42 and the artificial line AL to earth; the other portion traversing the relay coil 41, the main line 1, thence through the coils 11 and 12 of the relay 10 and the artificial line AL to earth. As well understood, this current action will be neutralized and non-effective in the relay 40, while in the relay 10 it will cause the armature thereof to bias to the side indicated by the conventional negative sign. In this position the armature of the relay 10 is held against its idle or non-connected stop and the path to the collector ring sections 34 and 37 of the distributor 30 is accordingly retained open. This operation serves to establish a uniform condition of the relay 10 and the distributor 30 during such periods as the trailer arms of the distributors are in their respective quadrants D and F. A source of current 6 included with the collector ring sections 32 and 33 of the distributor 30 is active when the trailer arm 31 is in the quadrant D to establish connection from a segment 7 to the section 32, and during the time the trailer arm 31 is in the quadrant F circuit is established from a segment 8 to the section 33. Connections which may be assumed as extending from the segments 7 and 8 control mechanisms related to printing operations at respective receivers assumed as connected from the segments in the quadrants C and E, as well understood in the art.

In order that manual or Morse operation may be substituted for the multiplex printer operation, switch blades 26 and 36 at station A may be moved to their respective points 28 and 38; a telegraph key 29 will thereby be substituted for the distributor 20 and a telegraph sounder 39 will be substituted for the receiving distributor 30. At the station B, moving the switch blades 46 and 76 to their respective points 48 and 78, a sounder 59 will be substituted for the receiving distributor 80, while a telegraph key 79 will be substituted for the transmitting distributor 70. Two-way manual telegraphic service may now be carried on over the duplex main line 1, as well understood in the art. It will also be obvious that the sounders 39 and 49 may be employed as indicating means for convenience in the testing and localizing of circuit interruptions which may occur in the multiplex working. A lamp signal 18 at station A and a similar signal 68 at the station B are respectively under control of the switches 16 and 66 for service in connection with testing, balancing of circuits, etc., as will be obvious to those skilled in the art.

In starting and initially bringing the distributors at stations A and B into synchronism, one with another, the Morse equipment may be conveniently employed for communicating such request from one station to the other. Accordingly, at station A a driving motor (not shown) will be started and the distributor arms 21 and 31 of the distributors 20 and 30, respectively, brought to a predetermined speed. At station B the starting switch 60 is manually operated, and separation of its contacts 61 and 75 respectively disconnects the conductor 77 extending to the distributor 80 and the conductor 62 extending from the motor magnet 56 to the contacts 51 of the relay 50, while the closing of its contacts 63 substitutes a ground at this switch for the ground obtained through the quadrants D and F at 80 the distributor 80 as already described. Alternate negative and positive impulses transmitted from the quadrants D and F of the distributor 20 traverse the main line 1 and reciprocate the armature of the line relay 40, whereby the relay 50 is worked to alternately energize the motor magnet 55 and thereby rotate the armature 54 as already described. Operation of the switch 60 also establishes its contacts 64 to include a magnet 67 to be operated over a circuit controlled by the contacts 51 of the motor control relay 50, in phase with the relay 40 as worked by control impulses in the line 1. This circuit may be traced from a source of current 69, the magnet 67, contacts 64 of the switch 60, contacts 51 of the relay 50 and the contacts 63 of the switch 60 to ground. The magnet 67 is equipped to operate a shutter 88 properly aligned adjacent black and white markings on a suitable revolving part of the motor 53. This arrangement permits the synchronism of the motor 53 to be noted by the stroboscopic method, as through a suitable opening or sighting range in which the shutter vibrates, the moving white and black markings will appear to be stationary when the motor is moving in synchronism with the incoming impulses from the transmitting distributor 20 at station A.

During periods the switch 60 may be held operated as described in connection with starting operations the motor magnet 56 will stand disconnected at the contacts 75 of this switch and therefore the motor will be started and brought to synchronism through the successive energizations of the driving magnet 55 only. These energizations will correspond with the arrival of negative impulses from the distant distributor 20 to close the contacts 45 of the relay 40 and thereby energize the relay 50 to close its contacts 52 as already described. The armature 54 of the motor will be impelled by momentum effects in absence of energization of the driving magnet 56, during intervals corresponding with the arrival of positive impulses from the distant station. Until the distributors at the remote

stations have been brought to a suitable state of synchronism, the transmitting equipments assumed as included in the quadrants C and E of the distributor 20 would, of course, continue idle, and a transmitter lever 4 in normally engaging its contact stop 5 in applying current from the positively poled source 3 to an associated message segment may be understood as typical of the arrangement (not shown) whereby the other segments in the message quadrants C and E are normally energized. The transmitter lever 4 may be shifted to engage its negatively energized stop 9 in combination with its associated levers (not shown) for the preparation of permutations of positive and negative impulses, as may be required in connection with the transmission of message signals from the segments in the quadrant C. It will, therefore, be clear that during intervals the transmitters may be idle as when starting operations are under way, the trailer arm 21 in sweeping through the quadrants C and E will establish positive currents over the line to bias the distant line relay 40 to close its contacts 44 and such condition of the circuits at the station B would be idle or ineffective, since the circuits of the motor 53 stand disconnected at the contacts 45 of the line relay while spacing effects only may take place with respect to the receiving equipments controlled from the quadrants C and E of the distributor 80 as well understood in the art.

Under full message capacity, it will be obvious that the trailer arms 21 and 81 of the distributors 20 and 80 respectively, will be effective during each revolution to alternately work in one-quarter periods message impulses and motor driving impulses over the main line 1. It will also be clear that one driving station equipped in accordance with the station A, may be employed to control the operation of a plurality of driven stations, each equipped in accordance with the station B.

What is claimed is:

1. In a telegraph system, a line circuit, a motor including driving magnets therefor, means for the alternate working of message and control impulses over said line circuit, a line relay and a relay responsive to said line relay for energizing the driving magnets to operate said motor.

2. In a telegraph system, a line circuit, a transmitting distributor and a receiving distributor for working groups of message and control impulses over said line circuit alternately, a motor including electromagnets for driving said receiving distributor, and a relay responsive to predetermined ones of said impulses to energize said electromagnets for driving said motor.

3. In a telegraph system, a line circuit, a line relay in said circuit, a plurality of distributors, a motor including driving magnets controlled through said line circuit to operate predetermined ones of said distributors, means controlled by said distributors for working impulses over said line circuit, and a relay controlled by said line relay and responsive to predetermined ones of said impulses to energize the driving magnets of said motor.

4. In a telegraph system, a line circuit, means for working impulses over said line, a motor, means for rendering predetermined ones of said impulses effective to drive said motor, and means for rendering other predetermined ones of said impulses effective for indicating when the speed of said motor is in synchronism with said impulses.

5. In a telegraph system, a first distributor, a second distributor, a line circuit and a line relay connected intermediate said distributors, a second relay jointly controlled by said line relay and said second distributor, a motor controlled by said second relay to drive said second distributor, means controlled by said first distributor for the transmission of impulses over said line, and means jointly controlled by said line relay and said second distributor for rendering predetermined ones of said impulses effective to operate said second relay.

6. In a telegraph system, a line circuit, a first distributor included with said line circuit, a line relay included with said line, a second distributor controlled by said line relay, a second relay controlled by said line relay and said second distributor, a motor controlled by said second relay to drive said second distributor, and means controlled by said first distributor for the alternate transmission of message impulses and control impulses to said second distributor to respectively effect message reception and the operation of said second relay to drive said motor.

7. In a telegraph system, a line circuit, transmitting and receiving distributor means for said line, motor means for operating said receiving distributor means, impulse receiving means for said line to control circuits of said receiving distributor means, means controlled by said impulse receiving means and said receiving distributor for effecting drive of said motor, and means controlled by said transmitting distributor to alternately transmit message impulses and impulses to work said means for effecting drive of said motor.

In witness whereof, I hereunto subscribe my name this 16th day of November, A. D. 1917.

AMOS F. DIXON.
